UNITED STATES PATENT OFFICE.

JOHN T. FITZPATRICK, OF MONTICELLO, OHIO.

DITCHING-MACHINE.

SPECIFICATION forming part of Letters Patent No. 291,043, dated January 1, 1884.

Application filed September 5, 1883. (No model.)

To all whom it may concern:

Be it known that I, JOHN T. FITZPATRICK, a citizen of the United States, residing at Monticello, county of Van Wert, and State of Ohio, have invented certain new and useful Improvements in Ditching-Machines; and I do hereby declare the following to be a description of the same, and of the manner of constructing and using the invention, in such clear, full, concise, and exact terms as to enable any person skilled in the art to which it appertains to construct and use the same, reference being had to the accompanying drawings, forming a part of the specification, the principle of the invention being herein explained, and the best mode in which I have contemplated applying that principle, so as to distinguish it from other inventions.

In the drawings, Figure 1 is a perspective view of the machine. Fig. 2 is a plan of the same. Fig. 3 is a detail view representing the driving-gear parts in inner side elevation. Fig. 4 is a detail view of the divided axle and clamping-boxes. Fig. 5 is a detail view of the scoop, the frame-work of the elevating-apron, the endless chains to which the slats of the apron are connected, and the shaft which drives said apron.

The main supporting frame-work is composed of two parallel beams, A, at a suitable distance from each other, and connected by cross-bars B.

C and C' are the two truck-wheels that carry the machine. C, the left-hand truck-wheel, is furnished with pawls h, (see Fig. 3,) attached to its spokes, adapted to engage with the cogs of the ratchet-wheel A'. This ratchet-wheel A' is rigid with the hub of the driving-wheel B'. The driving-wheel B' is adapted, by means of the ratchet-wheel and pawls, to be thrown in and out of gear with the truck-wheel C. C' is the right-hand truck-wheel.

The crank-axle is composed of two half parts, D and D', jointed, and adapted to allow each half to turn separately from the other when desirable. The abutting ends of the crank-axle are secured at their joint to the main frame-work by means of box e, that fastens them to the cross-bar D'. Each of the joining ends of the two-part axle is provided with a cylindrical head, e'. Said heads fit in transverse slot

e², formed in the center of the box e. The clamping-boxes e' also fasten the axle to the cross-bar D'. These clamping-boxes allow the axle to turn in them freely. The boxes e' 55 may be used as single or double boxes, the drawings illustrating the form of them, whether applied to both upper and under sides of the axle, or only to the under side.

Depending from the main supporting frame-work at its forward end are four braces, E, which converge at their lower ends, and carry a pioneer shovel-plow, F, riveted to them. The object of this plow is to level surface inequalities in the line of the proposed ditch, 65 and when not needed for this purpose it may be removed by the withdrawing of the bolts that fasten the supporting-braces E at their tops to the main frame.

Immediately back of the plow is the wheel 70 G, designed to maintain the machine at the proper depth. This wheel is suspended by four braces, H, having their upper extremities connected to the main frame in any suitable manner adapted to permit said rods to be 75 adjusted so as to cause the holes h in the front and rear sets to register for insertion of the axle-pin of wheel G, whereby the latter may be maintained at the desired vertical adjustment.

Immediately in rear of the wheel, and located 80 in a lower plane, is the scoop I, adapted to take up the mud or dirt as the machine moves, and to deliver it on the endless apron J. The frame-work of this apron J is bolted rigidly at the lower extremity to the rear end of the 85 scoop I.

K K are two upright cutters, secured respectively to the opposite lower corners of the scoop I by bolts. Each cutter is provided with a shank, K', formed in same piece therewith, 90 and extending forward and upward to the main frame, where it is secured to the said frame by a clamp, a. At the point where each cutter connects with its shank there is a bend or crook inward, k², adapted to prevent the shank from 95 striking against the sides of the ditch. The upper face of the scoop is provided with a dirt-breaker, f, located on its forward central portion. This dirt-breaker is adapted to keep the scoop from clogging. The scoop is also 100 provided with a rigid brace, o, secured by rivet i to the under side of its central portion. The

said brace extends rearwardly and upwardly, and is secured at its rear extremity to a depending staff, V. From this point of attachment two braces, *g g*, extend forwardly and upwardly to the side pieces, A, of the main frame.

The endless apron J revolves on the revolving shaft L, and is provided with adjusting devices adapted to tighten it and the sprocket-chain N'. This apron is furnished with sheet-iron sidings s, to confine laterally the dirt as it is transported to the discharging-apron M. The discharging-apron M is located transversely to the main body of the machine in rear of the elevating-apron J, and below its upper extremity, and is supported on the main frame-work. Adjusting devices are adapted to tighten said apron M. Said apron has a sheet-iron guard, t, on its rear side adapted to prevent the dirt from falling over its rear side into the ditch. The apron M projects sufficiently out on the right hand from the side of the machine to discharge the dirt clear of the ditch. Said apron turns on rollers *t' t'* at its extremities. The shaft of the driving-rollers *t'* is provided with the bevel-wheel N', that meshes in with the bevel-wheel O.

The bevel-wheel O and sprocket-wheel P are both fast to the shaft L. The sprocket-wheel P is driven by an endless chain, N', that connects it with the sprocket-wheel R. The sprocket-wheel R turns on the spindle d. The cog-wheel S is rigid with the sprocket-wheel R and meshes in with the driving-wheel B, the driving-wheel being revolved by the truck-wheel C when locked in with said wheel by the ratchet-wheel A' and the pawls h. At the rear end of the machine is a shoe, T, connected to the depending standard V by a set-screw, r', adapted to maintain it at any desired height thereon. The shoe is adapted to carry the rear end of the machine at any desired height.

X is the seat for the driver of the machine. Y is a hand-lever, rigid at its lower end in a shaft, j, and adapted to be operated by the driver for the purpose of raising or lowering the body of the machine. The shaft j has bearing on the two longitudinal beams of the main frame. The hand-lever Y being drawn toward the driver turns the shaft j, which carries the cog-wheel z that is rigid with it. The catch i is adapted to engage with this cog-wheel and to maintain the shaft j against reverse revolution. The shaft j is wrapped by two chains, k, each of which passes down under the main frame and hooks into an arm, l, respectively on each side of the machine, said arm being secured to the corresponding axle part at or near the junction of the crank portion with the axle-spindle.

Secured to the under face of each of the main frame-pieces A are pulleys l', under which run the chains that hook into the lever arms l. Normally the upper extremities of said lever-arms are above the horizontal plane of the pulleys, and are adapted to be pulled downward by the operating-chains. These arms l are provided each with two braces, m and m', each brace m being secured to the corresponding crank portion of the axle, about midway between the body of the axle and the axle-spindle, each brace m' being secured to the corresponding axle-spindle near its junction with the crank portion. This combination of hand-lever Y, revolving shaft j, cog-wheel z, chains k, arms l, pulleys l', and braces m and m' is adapted to adjust the crank-axle D D' more or less vertically over the hub-line of the truck-wheels C C', thereby raising or lowering the body of the machine.

X' is the traction-tongue of the machine with yoke and whiffletrees. Across the hub of the tongue is the stiffener o', which is held by staple-hooks y'. This stiffener o' is adapted to hold the tongue stiffly horizontal when the machine is not in use in the ditch.

What I claim is—

1. In a ditching-machine, the combination, with plow F and converging rods E, of wheel G, converging rods H, rear shoe, T, and standard V, substantially as set forth.

2. In a ditching-machine, the combination, with axle part D, having truck-wheel C mounted thereon, of axle part D', having truck-wheel C' mounted thereon, said axle part D' being provided with spindle d, having wheels R and S mounted thereon, substantially as set forth.

3. In a ditching-machine, the combination, with a crank-axle provided with arms l, of braces m and m', substantially as set forth.

4. In a ditching-machine, the combination, with oscillating crank-axle D D', of hand-lever Y, revolving shaft j, cog-wheel z, chains k, arms l, pulleys l', and braces m m', substantially as set forth.

5. In a ditching-machine, the combination, with scoop I and brace o, of depending standard V, shoe T, and adjusting device r', substantially as set forth.

6. In a ditching-machine, the combination, with axle part D', provided with spindle d, of wheels R and S, mounted on said spindle, substantially as set forth.

In testimony that I claim the foregoing to be my invention I have hereunto set my hand this 30th day of August, A. D. 1883.

JOHN T. FITZPATRICK.
